UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A HINGE.

SPECIFICATION forming part of Design No. 17,255, dated April 12, 1887.

Application filed March 21, 1887. Serial No. 231,776. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for a Hinge, of which the following is a specification, reference being had to the accompanying drawing, forming part thereof.

10 The only figure of said drawing is a front elevation showing the face side of the hinge. Each leaf has a plain border, *a*, inside of which is a like band or inner border, *b*, and the space between these two bands or borders is orna- 15 mented by a series of raised circular and oblong figures, as at *c d*. These borders (or compound border) form a panel, the face of which is mainly ornamented by palmate leaflets and scroll-work, the stems of which are arranged 20 as spreading in a cluster from the pintle side of each panel near the middle of its length, as

shown. The central portion of each ornamental tip *f* is ornamented by leaflets resembling those in the before mentioned panels.

I claim—

1. The design for a hinge herein shown and described, the same consisting of the leaves having the two border-bands *a b*, intervening series of circular and oblong ornaments, and leaflets and scroll-work on the face of the 30 panels.

2. The design for a hinge herein shown and described, the same consisting of the panel surface having ornamental palmate leaflets and scroll-work with their stems in a cluster 35 spreading from the pintle side of the panel near the middle of its length.

GEORGE S. BARKENTIN.
